(57) **CLAIM**

The ornamental design for a shower column, as shown and described.

DESCRIPTION

FIG. 1 is a first perspective view of a shower column showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion 9 in FIG. 1; and,

FIG. 10 is an enlarged view of the selected portion 10 in FIG. 1.

The broken lines shown in the drawings depict portions of the shower column that form no part of the claimed design. The dash-dot broken lines show enlargements and form no part of the claimed design.

1 Claim, 10 Drawing Sheets(56)
